UNITED STATES PATENT OFFICE.

WILLIAM JAMES FRASER, OF MILWAUKEE, WISCONSIN.

RECORDING SIGNALING SYSTEM.

SPECIFICATION forming part of Letters Patent No. 439,295, dated October 28, 1890.

Application filed May 17, 1890. Serial No. 352,212. (No model.)

To all whom it may concern:

Be it known that I, WILLIAM JAMES FRASER, a citizen of the United States, residing at Milwaukee, in the county of Milwaukee and State 5 of Wisconsin, have invented certain new and useful Improvements in Recording Signaling Systems; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

15 My invention relates to that class of recording signaling systems in which an electric circuit communicates with a central station and a number of subordinate stations or boxes, the electric circuit being used to send reports 20 from the boxes to the central station. In such systems such reports are usually recorded upon a rotating disk controlled by a clock, to the end that the apparatus shall show the time at which the reports were transmitted from the various boxes.

25 It is my object to produce such a system in simple and inexpensive form.

In the accompanying drawings, Figure 1 illustrates in a general way one form of embodying my improved system. Fig. 2 is a detail of means employed to operate the system. Figs. 3, 4, and 5 are details of the transmitting mechanism.

35 A is a disk for receiving the marking from the stylus. This disk may be of any suitable form, and is to be rotated by clockwork. As this part of the system is already well understood, I do not show the mechanism used to support and rotate said disk.

40 B B are boxes located at the several places to be visited by the watchman upon his rounds.

C is the conductor leading from the most remote of such boxes past each of the entire 45 series and thence to the central station, where the disk A is located.

50 Fig. 3 shows in detail the construction of the boxes. While the mechanism of these boxes resembles that of the break-wheel boxes used in the ordinary fire-alarm systems, it differs from such boxes to a certain extent in its construction, and radically in its operation in

conjunction with the apparatus at the central station. For the present it is sufficient to say that the wheel B' is to be rotated by 55 means of a key or otherwise. A brush B², communicating with the conductor C, bears continuously upon some surface of the wheel. Another brush B³, communicating with the ground through the conductor C', reaches into 60 the path of the teeth B⁴, so that when the wheel is rotated in the direction of the arrow said teeth make contact successively with said brush, and whenever such contact is made the circuit is completed from the central station through the conductor C, through the brush B², the wheel B', the brush B³, and conductor C' to the ground G.

D is the battery, preferably located at the central station on the conductor C², leading 70 from the stylus-operating mechanism to the ground G.

E is a wheel or disk provided with escape- 75 ment-teeth and located at a suitable distance from the disk A.

E' is an escapement-anchor engaging the wheel E and having its arm hinged at E². The function of the wheel may be performed if rotated in either direction. At one side of the arm of the anchor are located a pair of 80 magnets F. A portion of the conductor C² extends to such magnets and constitutes the coils of the latter, and then connects with the arm of the anchor E'. On the side of the arm of the anchor opposite the magnet F is located a contact-point F' in such position as to form a stop for the arm of the anchor at that side and to make electric connection between itself and the conductor C² through the arm of the anchor. A portion of the conductor 90 C leads to said contact-point. Then when the anchor-arm is in contact with the point F' the circuit is complete from the ground through the battery, the conductor C², the magnets F, anchor-arm, and conductor C to 95 the boxes B. Now when the brake at one of the boxes is closed the entire electric circuit is complete through the magnets F. When this occurs, the poles of said magnets are energized, so that they draw the anchor-arm to 100 them and away from the point F', thus breaking the circuit. When the circuit is broken, the magnets lose their energy, and the anchor-arm is returned by the spring F² again into

contact with the point F', so that the magnets F are again energized and again draw the anchor to them, only to allow it to again return by the action of the spring F². This 5 action is not in itself new. The anchor forms what is known to electricians as a "vibrating armature." It will be seen from the foregoing that as long as the circuit remains closed at one of the boxes the anchor E' will 10 vibrate and maintain the rotation of the wheel E, and that when such a wheel as is shown in in Fig. 3 is rotated by the watchman the anchor E' will vibrate intermittently. First 15 the circuit will be closed twice for a short period, then for a long period, then three times for a short period, and then again for a long period. The aggregate length of the contacts made by such teeth may be made sufficient to operate the anchor E' long enough to 20 give the wheel E just one rotation, the wheel B' being turned once by the watchman.

H, Figs. 1 and 2, is an arm extending from the wheel E to the disk A. At its upper end it bears a stylus H', which may be a puncturing or denting point or a pencil or a pen or other like device adapted to mark the disk A. Said arm extends through suitable guides, as H². At its lower end it is joined to the wheel E by a post E³, set at a suitable distance from 25 the center of the wheel E, so as to cause the latter to operate as a crank in reciprocating the arm H. The latter should have a joint at H³, in order that the upper portion of the arm may move in parallel with the guides H². 30 When at rest, before a report is to be transmitted, the wheel E should so stand as to bring the arm H to its lower limit.

It will now be understood that when the 35 circuit is closed at one of the boxes the anchor E' will vibrate and turn the wheel E so as to raise the arm H, and that if the circuit is kept closed long enough the arm H will continue to ascend until the wheel has made a half-rotation, and then descend to its lower limit. 40 If the circuit is made only long enough to partially raise the arm H, the latter will remain in such position to be further raised when the circuit is again closed, and so on until the wheel E has made a complete rotation and 45 turned the arm to the original position. The object in view in changing the position of the arm is to enable the stylus to produce marks at varying intervals, whereby the reports sent in from the various boxes may be distinguished. For instance, if a report is to be 50 sent in from box 24, it is intended to have the stylus produce two marks with a short interval between them, then a long interval, and then four marks with short intervals between 55 them. This I accomplish by causing the stylus to make an impression while at its lowest limit, then another at a point a little higher, then another after passing an interval which is long compared with the interval between 60 the first two marks, then one after passing each of three short intervals. The mechanism to be employed for causing the stylus to make

the impressions is a distinct branch or element of the apparatus or system. Different means may be employed for this purpose; but 70 I deem it sufficient to describe the form illustrated by the drawings.

I are a pair of magnets located behind the arm H. A portion of the conductor C² leads to and constitutes the coils of such magnets, and a portion of the conductor C leads from said magnets in the direction of the boxes. Under this arrangement the magnets I are connected in parallel with the magnets F, and there are no breaks in the portion of 80 the conductor upon which the magnets I are located. Consequently the magnets I become energized whenever the circuit is closed at one of the boxes, and so remain until such circuit is again broken at such box. Whenever 85 the anchor E' is vibrating, the magnets I are energized without interruption.

J is an armature located adjacent to the cores of the magnets I and held away from the latter by the spring J'. The armature J is 90 supported in any suitable manner—as, for example, by an arm J², extending at right angles from said armature. When the circuit is closed at one of the boxes, the armature J is drawn against the cores of the magnet I, 95 and the spring J' returns the armature to its normal position, as in the drawings, as soon as the magnets I de-energize upon the breaking of the circuit. This movement of the armature J is utilized mechanically to actuate the stylus H'. A hammer L, having a handle L', is pivoted at L², so as to bring the lower end of the handle immediately above the armature J and the head of the hammer 100 opposite the upper portion of the arm H.

J³ is any suitable projection supported by the armature J and extending into the path of the lower end of the handle of the hammer. Said projection is normally on the side of the handle L' opposite the magnets I. The weight of the hammer makes it tend to fall in the direction away from the arm H, while a spring L³ retains it in its normal position. On the side toward the magnets I the projection J³ is inclined, and the adjacent face of 110 the hammer is also inclined, and said projection may be made somewhat yielding. When the magnets I are energized, the armature J and the projection J³ are drawn toward the cores of said magnets, the projection J³ slipping by the lower end of the arm of the hammer without moving the latter, or moving it 115 but little. The parts in this position remain until the current through the magnets I is broken. Then the spring J' draws the armature J and projection J³ back to the normal 120 position. In doing so the projection J³ engages the end of the hammer-handle L and carries the latter with it a certain distance and then slips by such end. In thus moving 125 said end of the hammer-handle the hammer is tilted on its pivot L², the head of the hammer being carried away from the arm H. When the projection J³ slips by the lower end 130

of the hammer-handle, the spring L³, which has been stretched by the movement of the hammer-handle, recoils and quickly draws the hammer in the opposite direction, so that the 5 momentum acquired by the head of the hammer carries the latter into contact with the arm H' with sufficient force to drive the stylus against the disk A to mark the latter. It is to be remembered that the hammer L operates upon the breaking of the circuit at the 10 box operated by the watchman. If six marks are to be made upon the disk A to designate the box visited by the watchman, the break-wheel of said box must have at least six contact-points, and in order to effect an irregular 15 spacing of the marks made by the stylus in response to the strokes of the hammer the armature J must be held against the core of the magnets I during intervals varying in 20 length of time.

Referring now to Fig. 3, it will be understood from the foregoing explanation that as soon as tooth 1 makes contact with the brush B³ the stylus H' will begin to move forward; 25 but the circuit is soon broken, and upon breaking the hammer strikes the stylus. The entire mechanism at the central station is then at rest until tooth 2 makes contact with the brush B³. Then the stylus starts again to 30 travel upward; but the circuit is soon broken, and upon breaking the hammer again strikes the stylus, thus making another mark a little above the first. Then the mechanism is again at rest until the brush B³ makes contact with 35 tooth 3. The interval between tooth 2 and tooth 3 has no influence upon the distance between the marks made from said teeth to the disk A. The marking mechanism remains at rest whether such interval be long 40 or short. Tooth 3 has an elongated contact-surface, and the stylus travels upward during the contact with such tooth in proportion to the length thereof, and the stylus does not make another mark until the contact between 45 the brush B³ and said tooth breaks. Each of the teeth 4, 5, and 6 has a short contact-surface, and each such surface will cause the making of a short interval between two marks.

From the foregoing it will be seen that in 50 the operation of my system the interval between the marks made upon the disk A depends upon the length of the periods during which the circuit is closed, and not, as is usually the case with this kind of apparatus, upon 55 the spaces between the contact-points of the break-wheel.

The stylus will ascend during only the first half of the rotation of the wheel E, and during the remainder of the rotation it descends. 60 The marking upon the disk A should be done by either the ascending or descending movement of the stylus. I have described it as being performed during the ascending movement. The rotation of the wheel E may be 65 continued by means of the vibrating anchor until the original position is again attained. To effect the complete marking during the

ascent of the stylus, the aggregate contact-surface of the break-wheel teeth used for such marking must be less than the amount which 70 will cause the vibrating anchor E' to rotate the wheel E more than half-way around. By means of a prolonged contact made by the break-wheel the vibrating anchor may return the wheel E and the stylus H' to their original 75 position without having the latter make any further marks prior to the attaining of such original position. For this purpose a prolonged tooth 7 may extend from a point near the end of the brush B³ toward the tooth 80 6 a sufficient distance to make the aggregate contact-surface of all the teeth upon the break-wheel sufficient to cause the vibrating anchor to impart to the wheel E a complete 85 rotation. Then when contact has been broken with the last break-wheel tooth used for effecting the marking to designate the box the brush B³ will make contact with the tooth 7, be it long or short, and continue such contact until just before the complete turn of the 90 break-wheel has been effected. At this time the complete rotation of the wheel E and the return of the stylus H' have been effected. At this moment the contact between the brush 95 B³ and the tooth 7 is broken and the hammer 100 L again strikes the stylus; but the mark so made will be outside of the range of the marking which is to be read and no notice need be taken of it. Such a mark will be made at the conclusion of each operation of the apparatus.

The transmitting mechanism or boxes may be varied from the form shown in Fig. 3 without departing from the principle involved. For example, in lieu of the wheel B', a segment 105 of the wheel B' may be used, the teeth being grouped upon the segment as upon the wheel. Then in operating such transmitting mechanism the segment is moved through an arc of a circle equal to the periphery of the 110 segment.

In Fig. 5 the teeth are mounted upon a bolt or shaft, which is to be moved longitudinally to bring the teeth into contact with the brush B³. Thus in one case the movable part of 115 the transmitting mechanism is a wheel, in another a segment of a wheel, and in another a bolt or shaft.

I claim as my invention—

1. In a recording signaling system, a record-receiving surface, distant transmitting mechanism embracing electrodes grouped to conform to a character to be transmitted, an electric circuit extending from said record-receiving surface to said transmitting mechanism, a shifting stylus for marking upon said record-receiving surface, mechanism controlled by a magnet upon said circuit for shifting said stylus parallel to said record-receiving surface at intervals corresponding to the grouping of said electrodes, substantially as shown and described.

2. In a recording signaling system, a moving record-receiving surface at the receiving-

- station, distant transmitting mechanism, an electric circuit extending from said receiving-station to the transmitting mechanism, a shifting stylus for marking upon said record-receiving surface, mechanism controlled by a magnet upon said circuit for shifting said stylus, and mechanism controlled by a magnet upon said circuit in parallel with the magnet controlling said stylus-shifting mechanism for causing said stylus to operate upon said record-receiving surface when the condition of the circuit is made normal at the transmitting mechanism, substantially as shown and described.
15. 3. In a recording signaling system, a moving record-receiving surface at the receiving-station, distant transmitting mechanism, an electric circuit extending from said receiving-station to the transmitting mechanism, a vibrating armature having its magnets upon the circuit at the receiving-station, a shifting stylus adjacent to said record-receiving surface, shifting mechanism supporting said stylus and operated by said vibrating armature and its magnets, and mechanism arranged to cause said stylus to operate upon said record-receiving surface when the condition of the circuit is made normal at the transmitting mechanism, substantially as shown and described.
20. 4. In a recording signaling system, a moving record-receiving surface at the receiving-station, distant transmitting mechanism, an electric circuit extending from said receiving-station to the transmitting mechanism, a vibrating armature embodying an escapement-anchor arranged with its magnets upon said circuit at the receiving-station, an escapement-wheel operated by said anchor, an arm supported by said wheel eccentric to the latter and controlled by suitable guides, a stylus supported by said arm adjacent to said record-receiving surface when the condition of the circuit is made normal at the transmitting mechanism, substantially as shown and described.
25. 5. In a recording signaling system, a continuously-rotating record-receiving surface at the receiving-station, distant transmitting mechanism, an electric circuit extending from said receiving-station to the transmitting mechanism, a stylus for marking upon said record-receiving surface, mechanism controlled by a magnet upon said circuit for shifting said stylus, and mechanism controlled by a magnet upon said circuit in parallel with the magnet controlling said stylus-shifting mechanism for causing said stylus to operate upon said record-receiving surface when the condition of the circuit is made normal at the transmitting mechanism, substantially as shown and described.
30. 6. In a recording signaling system, a continuously-rotating record-receiving surface at the receiving-station, distant transmitting mechanism, an electric circuit extending from said receiving-station to the transmitting mechanism, a vibrating armature having its magnets upon the circuit at the receiving-station, a shifting stylus adjacent to said record-receiving surface, shifting mechanism supporting said stylus and operated by said vibrating armature, and mechanism controlled by a magnet located upon said circuit in parallel with the magnet controlling said vibrating armature and its magnets, such mechanism being arranged to place said stylus into operation with said record-receiving surface when the condition of the circuit is made normal at the transmitting mechanism, substantially as shown and described.
35. 7. In a recording signaling system, a continuously-rotating record-receiving surface at the receiving-station, distant transmitting mechanism, an electric circuit extending from said receiving-station to the transmitting mechanism, a vibrating armature embodying an escapement-anchor arranged with its magnets upon said circuit at the receiving-station, an escapement-wheel operated by said anchor, an arm supported by said wheel eccentric to the latter and controlled by suitable guides, a stylus supported by said arm adjacent to said record-receiving surface when the condition of the circuit is made normal at the transmitting mechanism, substantially as shown and described.
40. 8. In a recording signaling system, a continuously-rotating record-receiving surface at the receiving-station, distant transmitting mechanism, an electric circuit extending from said receiving-station to the transmitting mechanism, a stylus for marking upon said record-receiving surface, mechanism controlled by a magnet upon said circuit for shifting said stylus, and mechanism controlled by a magnet upon said circuit in parallel with the magnet controlling said stylus-shifting mechanism for causing said stylus to operate upon said record-receiving surface when the condition of the circuit is made normal at the transmitting mechanism, substantially as shown and described.
45. 9. In a recording signaling system, a continuously-rotating record-receiving surface at the receiving-station, distant transmitting mechanism, an electric circuit extending from said receiving-station to the transmitting mechanism, a vibrating armature having its magnets upon the circuit at the receiving-station, a shifting stylus adjacent to said record-receiving surface, shifting mechanism supporting said stylus and operated by said vibrating armature, and mechanism controlled by a magnet located upon said circuit in parallel with the magnet controlling said vibrating armature and its magnets, such mechanism being arranged to place said stylus into operation with said record-receiving surface when the condition of the circuit is made normal at the transmitting mechanism, substantially as shown and described.

10. In a recording signaling system, a continuously-rotating record-receiving surface at the receiving-station, distant transmitting mechanism, an electric circuit extending from said receiving-station to the transmitting mechanism, a vibrating armature embodying an escapement-anchor arranged with its magnets upon said circuit at the receiving-station, an escapement-wheel operated by said anchor, an arm supported by said wheel eccentric to the latter and controlled by suitable guides, and a stylus supported by said arm adjacent to said record-receiving surface, and means for bringing said stylus into contact with said record-receiving surface when the condition of the circuit is made normal at the transmitting mechanism, substantially as shown and described.

11. In a recording signaling system, a moving record-receiving surface at the receiving-station, distant transmitting mechanism, an electric circuit extending from said receiving-station to the transmitting mechanism, a stylus for marking upon said record-receiving surface, mechanism controlled by a magnet upon said circuit for shifting said stylus when the circuit is closed at the transmitting mechanism and mechanism controlled by a magnet upon said circuit in parallel with the magnet of said stylus, and shifting mechanism for causing said stylus to operate upon said record-receiving surface when the circuit breaks at the transmitting mechanism, substantially as shown and described.

12. In a recording signaling system, a moving record-receiving surface at the receiving-station, distant transmitting mechanism, an electric circuit extending from said receiving-station to the transmitting mechanism, a vibrating armature having its magnets upon the circuit at the receiving-station, a stylus adjacent to said record-receiving surface, mechanism supporting said stylus and operated by said vibrating armature when the circuit is closed at the transmitting mechanism, and mechanism controlled by a magnet located upon said circuit in parallel with the magnet of said vibrating armature, such mechanism being arranged to place said stylus into operation with said record-receiving surface when the circuit breaks at the transmitting mechanism, substantially as shown and described.

13. In a recording signaling system, a moving record-receiving surface at the receiving-station, distant transmitting mechanism, an electric circuit extending from said receiving-station to the transmitting mechanism, a vibrating armature embodying an escapement-anchor arranged with its magnets upon said circuit at the receiving-station, an escapement-wheel operated by said anchor, an arm supported by said wheel eccentric to the latter and controlled by suitable guides, a stylus supported by said arm adjacent to said record-receiving surface, and means for bringing said stylus into contact with said record-

receiving surface when the circuit breaks at the transmitting mechanism, substantially as shown and described.

14. In a recording signaling system, a continuously-moving record-receiving surface at the receiving-station, distant transmitting mechanism, an electric circuit extending from said receiving-station to the transmitting mechanism, a stylus for marking upon said record-receiving surface, mechanism controlled by a magnet upon said circuit for shifting said stylus when the circuit is closed at the transmitting mechanism, and mechanism controlled by a magnet upon said circuit in parallel with the magnet of said stylus-shifting mechanism for causing said stylus to operate upon said record-receiving surface when the circuit breaks at the transmitting mechanism, substantially as shown and described.

15. In a recording signaling system, a continuously-moving record-receiving surface at the receiving-station, distant transmitting mechanism, an electric circuit extending from said receiving-station to the transmitting mechanism, a vibrating armature having its magnets upon the circuit at the receiving-station, a stylus adjacent to said record-receiving surface, mechanism supporting said stylus and operated by said vibrating armature and its magnets when the circuit is closed at the transmitting mechanism, and mechanism controlled by a magnet arranged upon said circuit in parallel with said vibrating armature to place said stylus into operation with said record-receiving surface when the circuit breaks at the transmitting mechanism, substantially as shown and described.

16. In a recording signaling system, a continuously-moving record-receiving surface at the receiving-station, distant transmitting mechanism, an electric circuit extending from said receiving-station to the transmitting mechanism, a vibrating armature embodying an escapement-anchor arranged with its magnets upon said circuit at the receiving-station, an escapement-wheel operated by said anchor when the circuit is closed at the transmitting mechanism, an arm supported by said wheel eccentric to the latter and controlled by suitable guides, and a stylus supported by said arm adjacent to said record-receiving surface, and means for bringing said stylus into contact with said record-receiving surface when the circuit breaks at the transmitting mechanism, substantially as shown and described.

17. In a recording signaling system, a rotating record-receiving surface at the receiving-station, distant transmitting mechanism, an electric circuit extending from said receiving-station to the transmitting mechanism, a stylus for marking upon said record-receiving surface, mechanism controlled by a magnet upon said circuit for shifting the stylus when the circuit is closed at the transmitting mechanism, and mechanism controlled by a magnet upon said circuit in par-

allel with the magnet of said stylus-shifting mechanism for causing said stylus to operate upon said record-receiving surface when the circuit breaks at the transmitting mechanism, substantially as shown and described.

18. In a recording signaling system, a rotating record-receiving surface at the receiving-station, distant transmitting mechanism, an electric circuit extending from said receiving-station to the transmitting mechanism, a vibrating armature having its magnets upon said circuit at the receiving-station, a stylus adjacent to said record-receiving surface, mechanism supporting said stylus and operated by said vibrating armature when the circuit is closed at the transmitting mechanism, and mechanism controlled by a magnet located upon said circuit in parallel with the magnet of said vibrating armature, such mechanism being arranged to place said stylus into operation with said record-receiving surface when the circuit breaks at the transmitting mechanism, substantially as shown and described.

19. In a recording signaling system, a rotating record-receiving surface at the receiving-station, distant transmitting mechanism, an electric circuit extending from said receiving-station to the transmitting mechanism, a vibrating armature embodying an escapement-anchor arranged with its magnets upon said circuit at the receiving-station, an escapement-wheel operated by said anchor when the circuit is closed at the transmitting mechanism, an arm supported by said wheel eccentric to the latter and controlled by suitable guides, a stylus supported by said arm adjacent to said record-receiving surface, and means for bringing said stylus into contact with said record-receiving surface when the circuit breaks at the transmitting mechanism, substantially as shown and described.

20. In a recording signaling system, a continuously-rotating record-receiving surface at the receiving-station, distant transmitting mechanism, an electric circuit extending from said receiving-station to the transmitting mechanism, a stylus for marking upon said record-receiving surface, mechanism controlled by a magnet upon said circuit in parallel with the magnet of said stylus-shifting mechanism for causing said stylus to operate upon said record-receiving surface when the circuit breaks at the transmitting mechanism, substantially as shown and described.

21. In a recording signaling system, a continuously-rotating record-receiving surface at the receiving-station, distant transmitting mechanism, an electric circuit extending from said receiving-station to the transmitting mechanism, a vibrating armature embodying an escapement-anchor arranged with its mag-

nets upon said circuit at the receiving-station, an escapement-wheel operated by said anchor when the circuit is closed at the transmitting mechanism, an arm supported by said wheel eccentric to the latter and controlled by suitable guides, a stylus supported by said arm adjacent to said record-receiving surface, and means for bringing said stylus into contact with said record-receiving surface when the circuit breaks at the transmitting mechanism, substantially as shown and described.

22. In a recording signaling system, a moving record-receiving surface at the receiving-station, distant transmitting mechanism, an electric circuit extending from said receiving-station to the transmitting mechanism, a shifting stylus for marking upon said record-receiving surface, mechanism controlled by a magnet upon said circuit for shifting said stylus when the circuit is closed at the transmitting mechanism, and mechanism controlled by a magnet upon said circuit in parallel with the magnet of said stylus-shifting mechanism for causing said stylus to operate upon said record-receiving surface when the circuit breaks at said transmitting mechanism, such transmitting mechanism having teeth with sufficient aggregate contact-surface to close the circuit sufficiently in the aggregate to cause said stylus-shifting mechanism to shift said stylus through its full range of movement when the movable part of the transmitting mechanism is moved through its full range of movement, substantially as shown and described.

23. In a recording signaling system, a moving record-receiving surface at the receiving-station, distant transmitting mechanism, an electric circuit extending from said receiving-station to the transmitting mechanism, a shifting stylus for marking upon said record-receiving surface, mechanism having a magnet upon said circuit for shifting said stylus when the circuit is closed at the transmitting mechanism, and mechanism having a magnet upon said circuit in parallel with said stylus-shifting mechanism for causing said stylus to operate upon said record-receiving surface when the circuit breaks at said transmitting mechanism, such transmitting mechanism having a break-wheel with teeth having sufficient aggregate contact-surface to close the circuit sufficiently in the aggregate to cause said stylus-shifting mechanism to shift said stylus through its full range of movement when the break-wheel is moved through its full range of movement, substantially as shown and described.

24. In a recording signaling system, a moving record-receiving surface at the receiving-station, distant transmitting mechanism, an electric circuit extending from said receiving-station to the transmitting mechanism, a vibrating armature having its magnets upon the circuit at the receiving-station, a shifting stylus adjacent to said record-receiving surface, mechanism supporting said stylus and

an electric circuit extending from said receiving-station to the transmitting mechanism, a stylus for marking upon said record-receiving surface, mechanism controlled by
5 a magnet upon said circuit for shifting the stylus when the circuit is closed at the transmitting mechanism, and single-stroke mechanism having a magnet upon said circuit in parallel with the magnet of said stylus
10 shifting mechanism for causing said stylus to operate upon said record-receiving surface

when the circuit breaks at the transmitting mechanism, substantially as shown and described.

In testimony whereof I affix my signature, in 15 presence of two witnesses, this 24th day of March, 1890.

WILLIAM JAMES FRASER.
